COFFEE URN

Thomas G. Nevell, Riverside, Conn., assignor to Tricolator Company, Inc., New York, N. Y., a corporation of New York

Application March 30, 1950, Serial No. 8,867

Term of patent 14 years

(Cl. D44—26)

To all whom it may concern:

Be it known, that I, Thomas G. Nevell, a citizen of the United States of America, and resident of Riverside, county of Fairfield, State of Connecticut, have invented a new, original, and ornamental Design for a Coffee Urn, of which the following is a specification, reference being had to the accompanying drawing, forming a part thereof, in which

Fig. 1 is a top plan view of a coffee urn, showing my new design;

Fig. 2 is a front elevational view; and

Fig. 3 is a side elevational view thereof.

I claim:

The ornamental design for a coffee urn, substantially as shown.

THOMAS G. NEVELL.
